UNITED STATES PATENT OFFICE.

ROBERT H. READ, OF WASHINGTON, DISTRICT OF COLUMBIA, ASSIGNOR TO GENERAL ELECTRIC COMPANY, A CORPORATION OF NEW YORK.

ELECTRIC HEATER.

1,127,374.

Specification of Letters Patent.

Patented Feb. 2, 1915.

Application filed January 3, 1914. Serial No. 810,175.

To all whom it may concern:

Be it known that I, ROBERT H. READ, a citizen of the United States, residing at Washington, in the District of Columbia, 5 have invented a new and useful Improvement in Electric Heaters, of which the following is a specification.

This invention relates to electric heaters, the object being to improve the output of a 10 device of this character and its thermal efficiency by improving the thermal relation of the electrical heating element relatively to the heat transmitting support on which it is mounted.

15 In a prior application filed by me, Serial Number 485,329 I have described a heater of this character.

My present improvements relate to a particular form of connecting the heating elements in circuit with supply wires by which perfect freedom of expansion of the heater wire is afforded. The particular heating element employed in the present structure as 20 well as in that already referred to consists 25 of a high resistance heater-element formed of a metal or alloy of very high specific resistance surrounded by a closely packed powdered mineral insulation and inclosed in a metallic armor or sheath, the whole being 30 metallically united on the outside of the sheath with a heat transmitting plate to communicate by the best possible thermal relation the heat of the element to a body through which the heat is to be diffused 35 either by radiation or conduction. Now the metallic armor by reason of its rigid bond with the supporting plate is afforded small opportunity of expansion, the latter being absorbed incrementally by the support; the 40 resistance wire however being locked only by the hard packed mineral insulation is relatively comparatively free to expand and develops a strain at the ends where it is connected to an external circuit, forcing the 45 joint at that point to be distorted or to give way. Moreover the heating element or core wire itself if allowed to protrude from the powder or insulation becomes highly heated where it is bathed in the air and by repeated

flexure under successive heatings and cool- 50 ings is liable to break off.

My present improvements are directed to a cure for both of these objectionable features, in that I provide for the expansion of the core-wire by a flexible connection or lead 55 connecting the same with the fixed circuit terminals and in that I also terminate the core within the end of the wire itself where it is surrounded by insulating powder, connecting it at its terminus with a lead-wire of 60 greater conductivity, as for example, one of greater cross-section or one of less specific resistance, which will not heat under the normal amperage of the current carried by 65 the core wire.

My invention therefore comprises an electric heater consisting of a resistance heating-element embedded in heat refractory mineral insulation and inclosed within a metallic armor with leads so connected with a 70 supply circuit as to permit relative movement of the armor and core wire without strain.

It comprises also such a heater having its core wire of high specific resistance con- 75 nected by a joint with a better conducting terminal, which joint is afforded heat diffusing means to prevent excessive heating of the core-wire.

Other features of novelty of my invention 80 will be more particularly hereinafter described and will be definitely indicated in the claims appended to this specification:

In the accompanying drawing which illustrates my invention: Figure 1 represents a 85 portion of a heater very much magnified in dimensions embodying my improvements. Fig. 2 is a view of the device shown in Fig. 1 shown on a plane at right angles to that of the latter figure. Fig. 3 is a similar view 90 to Fig. 2 showing a modification in which a ribbon terminal is employed, and Fig. 4 is a bottom plan showing on a small scale the heating element and its radiator according to my invention. 95

Referring now more particularly to the drawings, 1 represents a radiator or heat diffuser consisting of a metallic plate which

may form part of a heating vessel or any desired object to be heated. Metallically secured thereto by soldering or electrical welding or other integral means of forming 5 a metallic union with the plate is an armored wire consisting of a core-wire 2, surrounded by mineral insulation 3, both being inclosed in a tubular metallic shell 4.

I have heretofore fully disclosed a wire of 10 this kind in other applications, as for example, that above referred to; the core wire 2 is made of metal or alloy of high specific resistance such as nickel iron, nickel chromium or nickel manganese. The refractory 15 insulating powder should be highly compacted between the core-wire and its armor 4, and is preferably of a composition sufficiently heat refractory not to approach its fusing point at the temperatures to which 20 the core-wire is run in service, such as material made of such mineral oxids or silicates as finely divided flint, magnesia, kaolin, soap-stone, or in general any material which is at once a good insulator and fairly good heat 25 conductor and has a high fusing point. I have found excellent results with finely divided flint of a high degree of fineness which in the process of manufacture of the armored conductor is highly compacted within 30 the armor and affords an easy path for diffusing heat given off by the core and its transmission to the supporting plate or any medium which surrounds it. This wire is 35 preferably wound in a spiral as indicated in Fig. 4 both ends being carried spirally outward and terminating on the exterior of the supporting plate in binding posts or other terminals 5-5^a by which communication with a supply-circuit may be made.

40 At the point where the lead wires are joined to the supply circuit I provide a yielding terminal 6-6^a; this may be a simple helix by which flexibility relative to the fixed terminals is afforded, or it may be a 45 tape-like lead 7, see Fig. 3, sufficiently flexible to yield and provide for such expansion as may be created by the heat. I preferably make this yielding terminal of material of better conductivity than the core-wire and 50 joint it with the latter so that the joint is relatively cool compared to the temperature of the core-wire itself; this may be effected in a variety of ways as for example by making the terminals of a good conducting metal 55 as copper and inclosing the joint with the core-wire within a heat diffusing medium. One convenient way of effecting this result is to form a tubular terminal 9 united by solder or otherwise with the armor and filling it with a heat refractory powder, as flint, whereby the joint is in good thermal relation to the tubular tip 9 maintained relatively cool by the radiating surface of the

tube which may be extended if desired by one or more metallic radiators 10, secured to the tip. In fact the projecting terminals 6-6^a if of copper will by reason of its high conductivity carry away heat from the joint sufficiently fast to keep the latter at a relatively low temperature. Where the terminal protrudes is a lava or soap-stone bushing 11 around which the terminus of the tip is crimped, as indicated at 12, to form a secure mounting for it. Thus it will be seen that the armored heater wire is in rigid relation to the support and that the core wire is free to expand relatively thereto without producing strain on the fixed terminals or on itself.

I do not claim in this application a core-wire of high resistance in a seamless tube, with a closely compacted powder insulation, such matter being claimed in my copending application #841,544, filed May 28, 1914.

Having thus fully described my invention 85 what I claim as new and desire to secure by Letters Patent in the United States, is:

1. An electric heater comprising an armored wire consisting of a core of high specific resistance, a refractory insulating powder surrounding the same and inclosed within a metallic tube, and terminals connecting with a supply circuit free to accommodate relative movement of the armor and core-wire to relieve strain on the core-wire. 95

2. An electric heater comprising a heat distributing plate, an armored heater wire metallically bonded thereto and inclosed within a metallic tube, a spacing of heat refractory mineral insulation between the wire 100 and its armor, and flexible terminals connecting the wire with fixed supply-circuit terminals.

3. An electric heater comprising an armored wire of high specific resistance, the armor being metallic and confining the wire centrally within a body of heat refractory mineral insulation, and a terminal of relatively greater current carrying capacity than the wire connected thereto by a metallic 110 joint, said terminal being adapted to yield relatively to the fixed circuit-terminal.

4. An electric heater comprising an armored wire of high specific resistance, the armor being metallic and confining the wire 115 centrally within a body of heat refractory mineral insulation, and a terminal of relatively greater current carrying capacity than the wire connected thereto by a metallic 120 joint, said joint being surrounded by a heat radiating surface to keep it cool.

5. An electric heater comprising a heat distributing plate metallically bonded with an armored resistance wire comprising a core-wire of high specific resistance, a 125 tightly packed refractory mineral insulation,

a tubular metallic armor, a terminal therefore extending through a tip of insulating material, and a heat radiator for keeping the terminal cool.

5 6. An electric heater comprising a heat distributing plate and an armored wire metallically bonded thereto, said wire being composed of a core wire of high specific re-

sistance, a packing of heat refractory mineral insulation and a tubular armor, the wire 10 being flexed spirally from the center outward at both ends.
